UNITED STATES PATENT OFFICE.

OSCAR A. ROSS, OF BROOKLYN, NEW YORK.

AUTOMATIC TRAIN-CONTROL SYSTEM OR THE LIKE.

1,389,220.

Specification of Letters Patent. Patented Aug. 30, 1921.

Application filed January 9, 1917. Serial No. 141,404.

To all whom it may concern:

Be it known that I, OSCAR A. ROSS, a citizen of the United States and residing at 55 Hanson Place, city of Brooklyn, county of 5 Kings, State of New York, have invented a new and useful Improvement in Automatic Train-Control Systems or the like, of which the following is a specification.

My improved system pertains to a complete system of automatic train control for vehicles, or trains operating on a permanent right of way and has for its more prominent objects the attainment in a more economical and effective manner of the results or operations specified herein.

Primarily the purpose in view is to compel the operator of a vehicle, or train to reduce speed when approaching a zone of hazard, such speed reduction being preferably in accordance with signals placed along the roadway of said vehicle, at the same time however, permitting said vehicle to enter said zone of hazard at a predetermined reduced speed, thereby increasing "capacity" 25 or number of trains which can pass a given point in a given length of time, and as fully described in my application for Letters Patent Serial #113,064 dated August 4th, 1916.

It is further the aim of my improved system to impose such speed reduction in a manner that will permit two or more trains, or vehicles, to operate with safety at practically normal braking distance apart, thereby obtaining practically maximum "capacity" or service when required.

A further aim is to secure a high degree of flexibility with respect to developing the various speed reductions demanded by the several constructional conditions existing 40 along the right of way of said vehicle, or train.

A further aim of my improved system for reducing the speed of trains, or vehicles, when approaching a zone of hazard, is to compel said train, or vehicle to come to an "absolute stop" at locations of extreme hazard, as for example at a crossing of an adjacent railway, or switch, connection therewith, and at which points is usually placed 50 an interlocking tower.

A further object of my improved system for reducing the speed of trains, or vehicles when approaching a zone of hazard, is to compel said train to reduce its speed to a 55 given value and thereafter continue at such

reduced speed until proper signals indicate to the motorman or operator of said train that maximum speed may be resumed. Such speed reduction and operation is required at points on a roadway where curves, or minus grade, or minus grade preceding a curve exists, and where it would be hazardous to travel at maximum speed continuously.

A further aim of my improved system for reducing the speed of trains when approaching zones of hazard, is to adapt the various circuits and instrumentalities in a manner such, that said train may operate in a direction other than that of normal traffic, and which is known as "against traffic" and as 70 more fully pointed out in my application for Letters Patent Serial #128,817 dated November 1st, 1916. It is well known that accidents beyond the control of managers of railway systems require operation of trains 75 in a direction opposite to that of normal travel. Therefore in a complete system of automatic train control means must be provided for such "against traffic" moves.

A further aim of my improved system for reducing the speed of trains when approaching zones of hazard, is to adapt the various circuits in a manner to permit said train to travel from territory equipped with automatic train control apparatus into territory 85 not so equipped and known as "unsignaled territory", at the same time indicating to the operator of said train that he is traveling in such territory. It is well known that on railway systems there are sections of the 90 roadway where it is imperative that signals and even automatic train control apparatus be installed for the protection of traffic, while at other points signals alone or even total absence of signals is permitted, as for 95 instance on sections known as divisions and where only one train operates at a time.

A further aim of my improved system for reducing the speed of trains when approaching zones of hazard, is to compel operators of said trains to make certain manual operations whereby the automatic train control apparatus on said train becomes effective to control the train in response to the apparatus on the roadway and before 100 said train can be propelled under its own power, and further in connection with such manual operations to record each time the automatic train control apparatus has been cut in or out of service.

A further aim of my improved system for reducing the speed of trains when approaching zones of hazard, is to arrange circuits and apparatus in a manner such that when 5 said trains are out of service all the train control apparatus on said train becomes operative by the coöperating automatic train control apparatus on the roadway.

A further aim of my improved system for 10 reducing the speed of trains when approaching zones of hazard, is to pre-arrange circuits and apparatus in a manner such that when a train composed of several cars, each car equipped with substantially similar automatic train control equipment is operated 15 over a railway system, only the automatic train control apparatus on the first, or leading car is arranged to be acted upon by the train control apparatus on the roadway.

20 This is known as "single car" control.

A further aim of my improved system of automatic train control, is to arrange circuits and apparatus such that a train, or car equipped with my system may be operated 25 from either end with equal facility and without affecting proper functioning of the automatic train control apparatus. It is well known that certain forms of vehicles termed cars equipped with multiple unit 30 control are arranged with duplicate sets of control, one arranged at each end of the car in what is termed the motorman's cab.

A further aim of my improved system of 35 automatic train control, is to compel the motorman, or operator of the train to cause certain important devices, employed in applying the brakes to the train, to function before placing said train in service. It is well known that any automatic train control 40 system depends upon some form of valve for applying brakes to the train, it is therefore essential to prove that such valve is operating properly before said train is placed in service.

45 A further aim of my improved train control system, is to check the presence in its proper location, of all important appliances employed in connection with said system. It is evident that in systems employing contact shoes and third rails as a means 50 for obtaining the indication from the right of way to train that absence of a contact shoe would prevent proper functioning of the system. It is therefore advisable to 55 check the presence of such a device.

My improved system has further the merit and advantage that it comprises a minimum number of devices and parts to meet all requirements now known to the 60 railway signaling and automatic train control art; that it is admirably adapted for installation in conjunction with existing block signal systems at a relatively small expense, and that when employed with 65 what is known in the art as a system of light

signals, it is, I believe the cheapest to install, the most economical to maintain and the most reliable in operation.

All the above and other objects and aims attained by the system which, for purposes 70 of specific illustration, is shown in the accompanying drawings, in which,

Figure 1, is a diagrammatic view of the circuits and apparatus located on a train, or car, or moving vehicle, showing also a part 75 of the right of way on which said train, car, or vehicle travels, with partial circuits and apparatus therefor.

Fig. 2, is also a diagrammatic illustration 80 of circuits and apparatus along the roadway upon which said train, or car, travels and involves the particular arrangement of circuits and apparatus employed in connection with certain circuits and apparatus shown in Fig. 1, which compel a predetermined reduction in speed of trains when approaching a zone of hazard.

Fig. 3, is also a diagrammatic illustration 85 of circuits and apparatus along the right of way upon which said trains travel and involves the particular circuits and apparatus employed in connection with certain circuits and apparatus shown in Fig. 1, and which permits said trains to travel from "signaled territory" to "unsignaled territory."

Fig. 4, is also a diagrammatic illustration 90 of circuits and apparatus along the right of way upon which said trains travel, and involves the particular circuits and apparatus employed in connection with certain circuits and apparatus shown in Fig. 1, and which compel a train to come to an "absolute stop" and remain so until proper signals are given to proceed.

Fig. 5, is also a diagrammatic view of circuits and apparatus along the right of way 100 upon which said trains travel, and involves the particular arrangement of circuits and apparatus employed in connection with certain circuits and apparatus shown in Fig. 1, which compel trains to operate at predetermined reduced speeds over sections of right of way where it would be hazardous to exceed such reduced speed.

None of the several appliances employed in this system, are, or need be, of any special, or unusual form, or construction, but for a more ready understanding of the system and of its operation, a preliminary description 110 of the appliances, or devices employed may be apposite.

Description of appliances shown in Fig. 1.

Train X¹ with circuits and apparatus, as 125 shown, is preferably assumed to be a single car, electrically propelled and generally known as having "multiple unit control". The several appliances located on car X¹ are as follows: A slow acting relay SAR, 130

comprises suitable energizing coil and core, the movement of which is restrained, or retarded in a proper manner, as, for example, by a dashpot DP, the piston of which is connected to the movable core. Said core is connected with, or moves circuit controlling levers 1, 2, and 3.

Another device is a quick acting relay C, composed of any suitable coil and core, or 10 armature and is arranged to operate two contact levers 4, and 5.

Another device is likewise a quick acting relay SR, termed a stick relay having two energizing coils PW, and SW, also two 15 movable cores, or armatures co-acting to operate contact levers 7, 8, 9, and 10.

Still another device is likewise a quick acting relay AT termed "against traffic relay". This relay also has suitable coil and 20 core co-acting to operate contact levers 11, 12, 13, 165, and 14.

Another device is likewise a quick acting relay UT, termed "unsigned territory relay". This relay also has a suitable coil and 25 core co-acting to operate contact levers 15, 16, and 17.

Another device is a cab signal panel, not shown, one of which is placed at each end of car X¹ in the motorman's cab. This light 30 panel contains the lights G, Y, W, R, and checking lamp 163, which are employed to guide the motorman with respect to performance of the automatic train control apparatus.

Another device is an electro-pneumatic valve EPV, shown as a rectangle at the right of the drawing. This valve is preferably 35 of the construction as pointed out in my Letters Patent #1,072,507 granted to me 40 Sept. 9th, 1914 with the exception that a back contact 18, has been added for use in connection with the "reset" circuit to be described later.

Other devices are two similar circuit controlling appliances KS¹, and KS², mounted 45 at each end of the car and adjacent to master controllers MC¹, and MC². These circuit controlling devices are arranged to be operated by a key, as 6, which when inserted 50 and rotated will raise contact levers 19, 20, 21, and 22, or 23, 24, 25, and 26, dependent upon which controller is placed in service. They key after being inserted and rotated as described cannot be removed until said 55 contact levers are lowered to their inoperative position as shown in device KS². Also each time said key is inserted and rotated a registration is made through a counter. It is to be noted that device KS¹, indicates 60 the numeral 1, thereby pointing out that said device has been operated for the first time.

Another device is a storage battery SB of well known construction the negative side 65 of which is grounded to the frame work of

car X¹. Said battery supplies energy to the various circuits and appliances required on the car in connection with my improved system of automatic train control.

Other devices are two contact shoes CS¹, 70 and CS². These shoes are attached to but insulated from car X¹, and for purposes which will be more fully described hereinafter, are preferably placed at the extreme ends and on opposite sides of the car X¹, as 75 shown in Fig. 1. Contact shoe CS², is rigidly connected to contact levers 27, 28, 29, 30, 31, 32, 33, and 34, through rod 35. Contact shoe CS¹ is of similar construction and operates contact levers 36, to 43, inclusive. As said 80 shoes pass over ramps as 2^B, and 3^B, they are raised, thereby raising said contact levers into front contact position.

As all other devices on the car X¹, and likewise those on the right of way, with 85 such exceptions as may hereinafter be more fully described, are of the usual forms, they will be sufficiently understood from the conventional figures employed to illustrate them.

My improved system in its operation involves and requires certain distinct, but more or less cooperative circuits, and these may be appropriately designed and described individually.

Description of train or car X¹, out of service.

Assume car X¹, Fig. 1, to be out of service. Both master controller handles, for well known reasons will be in neutral position. 100 Also, circuit controlling devices KS¹, and KS², will be without a key and therefore their levers will be in the lower position. By this arrangement a circuit is established direct to the valve EPV, as follows: 105

Out of service EPV circuit.

From battery SB, wire 47, fuse 48, wires 49, 50, lever 25, wire 51, lever 21, wires 52, and 53, to EPV valve, returning to battery 110 through ground on car. This circuit serves to maintain the automatic brake applying valve inoperative when car X¹, is out of service or in case said car is employed other than a first car of a train made up of several cars. With devices KS¹, and KS² inoperative energy from battery SB, is cutoff 115 from all other devices through levers 22, and 26.

Description of placing car X¹ in service.

Assume now it is desired to operate a car, as X¹, for purposes of transportation and that said car is the leading car in a train composed of several cars, or as an alternative may be operating as a single car train and traveling in the direction of arrow W. Under these conditions the motorman, or operator of train would insert and rotate key in device KS¹, thereby raising levers 19, 125 130

20, 21, and 22, and performing the following functions.

As lever 19 closes a partial circuit is established through wires 55, and 56, which with proper manipulation of master controller MC¹ will permit car X¹, to move forward under its own motors. By this arrangement it is evident that it becomes necessary to insert and rotate key in either device KS¹, or KS², before a train, or car can be propelled under its own power, and further as this operation also makes all the automatic train control devices located on the train responsive to the devices placed on the right of way, it is evident that a train cannot be moved without the protection of the automatic train control system.

As contact lever 20 is raised, a partial circuit is established for use in connection with the "against traffic" circuit to be described hereafter.

As lever 21 raises it opens the out of service EPV circuit and applies brakes to the train, thereby checking the operation of valve EPV.

Valve EPV, is also equipped with a counter of similar construction to that employed on devices KS¹, and KS², and as the valve is assumed to have operated for the first time the numeral 1, is shown. It is preferred to have motormen take record of the readings of said counter when placing a train in, or out of service. In this manner a check is obtained on the number of times said valve EPV, or device as KS¹, has been operated during the period of service. As is well known it is customary to equip all automatic block signals with such recording devices.

As valve EPV, operates to apply brakes to train as heretofore described, it lowers lever 18, thereby establishing the following partial circuit:

Reset circuit:

From battery SB, wire 46, and 57, push-button PB, wire 58, reset bus-line 59, (reset bus-line extends through all cars of a train and resets all valves or circuit breakers which may have been tripped by means known or unknown) wire 60, lever 18, wires 61, 77 and 62, to pick-up winding of stick relay SR, returning to battery through wire 78 and ground. As relay SR, picks up and raises levers 7, 8, 9, and 10, the following circuits are established, that is, assuming shoe CS¹, or CS², is not in contact with a ramp, as 2^B, or 3^B.

Stick circuit for stick relay SR.

From battery SB, wires 46, 47, fuse 48, wire 63, lever 22, wires 64, 65, 66, 67, 68, 69, 70, 71, 72, lever 39, wire 73, lever 30, wires 74, 75, lever 7, wires 76, 77, and 62, to coil PW, of relay SR, returning to bat-

tery SB, through wire 78, and ground. This circuit not only serves to restore valve EPV, but also serves to keep said valve inoperative while a train as X¹, is passing through a caution block as will be more fully hereinafter described. Further it also serves to prevent relay SR, from prematurely opening, in which case a contact shoe as CS¹, or CS², might be sufficiently in contact with a "caution" ramp to shunt out control relay C, but not sufficiently raised to close lever 28, or 37, thereby supplying energy direct to valve EPV, and as will be more fully hereinafter described.

As relay SR, is stuck up by the above described circuit its lever 8, supplies energy to the valve EPV, as follows:

EPV circuit through stick relay SR.

From battery SB, wires 46, 47, fuse 48, wire 63, lever 22, wires 64, 65, 66, 79, lever 8, wires 80, 81, 53, valve EPV, returning to battery through wire 82, and ground. This circuit keeps valve inoperative while contact shoes as, CS¹, or CS², are passing between ramps, as 2^B, and 3^B, in signaled territory and in the direction of arrow W. Said signaled territory is assumed to be equipped with automatic train control apparatus as illustrated in Figs. 2, 3, 4, and 5.

Lever 10, of stick relay SR, closes a partial circuit for use in connection with the "against traffic" moves to be more fully hereinafter described.

Simultaneous with inserting and rotating key in device KS¹, a circuit is established to caution cab signal Y, as follows:

Caution cab signal circuit.

From battery SB, wires 46, 47, fuse 48, wire 63, lever 22, wires 64 and 83, lever 5, in lowered position, wire 84, lever 14, wire 85, to lamp Y, returning to battery through wire 86, and ground. Whenever this circuit is established the train must be operated at reduced speed. It is established each time a train enters a caution block.

Description of movement of train X¹ in connection with Fig. 2.

Assume now that the train X¹, moves from its shelter to a portion of the roadway as illustrated by Fig. 2. As before stated said figure illustrates a section of roadway equipped with circuits and apparatus adapted, in co-operation with certain circuits and apparatus on train X¹, to compel reduction in train speed substantially in accordance with certain predetermined curves, one of which is shown as Z, in Fig. 2.

As the caution light Y, is illuminated, the motorman will operate his train at reduced speed until a clear ramp and signal, as 1^A, and 7^A are encountered. As train X¹, proceeds along roadway in the direction of ar-

row W, and encounters a ramp, as I^B , contact shoe CS^2 , is raised thereby raising levers 27 to 34 inclusive to their front contact positions. By this operation the following 5 circuits are consecutively established:

Slow acting relay circuit.

- From battery SB, wires 46, 47, fuse 48, wire 63, lever 22, wires 64, 65, 66, 67, 87, 10 88, 89, lever 31 in upper position, wires 90, 91, to coil of slow acting relay SAR, returning to battery through wire 92, and ground. If shoe CS^1 , had been the operative shoe the circuit would have terminated 15 as follows: branching from wire 67, to wires 68, 69, 70, 101, lever 40, in raised position wires 102, 91, to relay SAR, returning to battery. For purposes of illustration relay SAR, is assumed to require one second 20 to move contact levers 1, 2, and 3, to closed position. The primary object of this circuit is to compel motorman to operate his train such that in caution, or reduce speed blocks, as indicated by block C, Fig. 2, a contact 25 shoe as CS^2 , must consume at least one second or greater in passing over a ramp to prevent automatic application of brakes by valve EPV and as will be more fully pointed out as the description progresses.
- 30 Simultaneous with establishing the slow acting relay circuit the following circuit is established:

EPV circuit through contact shoe.

- 35 From battery SB, wires 46, 47, fuse 48, wire 63, lever 22, wires 64, 65, 66, 67, 87, 88, 93, 112, 113, lever 28, in raised position wire 95, lever 38, in lower position, wires 96, 97, 81, 53, valve EPV, returning to battery through wire 82, and ground. If shoe CS^1 , had been the operative shoe in place of CS^2 , the circuit would have been completed as follows: branching from wire 67, to wires 68, 69, 70, 71, 98, lever 37, in raised 40 position, wire 99, lever 29, in lowered position wires 100, 97, 81, 53, valve EPV, returning to battery through ground. The object of this circuit is to maintain valve EPV, inoperative the entire period either shoe 45 CS^1 , or CS^2 , may be in substantial contact with a ramp, as I^B , Fig. 2. It is to be noted that as shoe CS^2 , raises on ramp I^B , lever 30 opens the stick circuit for stick relay SR. However lever 28, is so adjusted that it 50 closes circuit to valve EPV, before lever 30, open the circuit to stick relay SR, therefore the circuit to said valve is not interrupted.

Assume that in obedience to the caution 55 cab signal Y, established by reset circuit the motorman has approached ramp I^B , at sufficient reduced speed to consume more than one second to pass over said ramp and under which conditions slow acting relay SAR, will complete movement of levers 1,

2, and 3. Lever 1, closes the following circuit:

EPV circuit through slow acting relay SAR.

70

From battery SB, wires 46, 47, fuse 48, wire 63, lever 22, wires 64, 65, 66, 67, 68, 69, 103, lever 41, wires 104, 105, 106, lever 1, wires 107, 108, 81, 53, valve EPV, returning to battery through wire 82, and ground. If shoe CS^1 , had been operative in place of shoe CS^2 , the circuit would have been completed as follows: branching from wire 67, to wires 87, 109, lever 32, wires 110, 111, 106, lever 1, wires 107, 108, 81, 53 to valve EPV, returning to battery through ground. The object of this circuit is to supply current to the valve EPV, and maintain it inoperative a predetermined time after a shoe as CS^1 , or CS^2 , has passed onto a ramp 85 as I^B , Fig. 2. It serves particularly to keep said valve inoperative while the various translating devices, or relays assume their positions as a contact shoe leaves a ramp.

90

As lever 2, of relay SAR, completes its movement the following partial circuit is established:

Pick-up circuit for control relay C.

95

From battery SB, wires 46, 47, fuse 48, wire 63, lever 22, wires 64, 65, 66, 67, 87, 88, 93, 112, 113, resistance 114, lever 27, and as the shoe CS^2 , leaves ramp I^B , and is lowered, the circuit is thereby completed 100 through wire 115, lever 36, wires 116, 117, lever 2, wires 118, and 119, to coil of control relay C, returning to battery through ground. If shoe CS^1 , had been the operative shoe the circuit would have been completed through lever 36, as said shoe left the particular ramp it was passing over. The object of completing this circuit just as a contact shoe leaves a clear ramp is to prevent as far as possible continuous flow 110 of current from battery SB, through resistance 114, in case a contact shoe engages and remains for some time in contact with a caution ramp as I^C , in Fig. 2, and which is short circuited to the track rails 45, and 115 as will be described under portion of reduce speed circuit on roadway.

105

As lever 3, of relay SAR, completes its movement the following circuit to relay SR, is established.

120

Pick-up circuit for stick relay SR through relay SAR.

From battery SB, wires 46, 47, fuse 48, wire 63, lever 22, wires 64, 65, 66, 67, 68, 69, 125 103, lever 41, wires 104, 105, 106, 106, lever 105, wire 120, lever 3, wire 121, to coil SW, of relay SR, returning to battery through wire 123, and ground. If shoe CS^1 , had been the operative shoe the circuit would 130

have been completed through lever 32 in place of 41, as described. The object of this circuit is to pick up relay SR, and keep it energized until the stick circuit for stick relay SR, is established as the shoe leaves the ramp.

When control relay C, is energized as shoe CS², leaves ramp 1^B, it establishes three circuits through its contact levers 4, and 5, 10 as follows; through lever 4,

Stick circuit for control relay C.

From battery SB, wires 46, 47, fuse 48, wire 63, lever 22, wires 64, 65, 124, 125, resistance 126, lever 4, wire 127, shoe CS¹, wire 128, shoe CS², wires 129, and 119, to coil of relay C, returning to battery through ground on car X¹. This circuit serves to keep relay C, energized after it has been 20 picked up through the pick-up circuit for control relay C, previously described, and while the contact shoes are passing between, or over clear ramps, as 1^B, and 2^B, Fig. 2.

The following two circuits are established 25 through lever 5, of control relay C:

Proceed cab signal circuit.

From battery SB, wires 46, 47, fuse 48, wire 63, lever 22, wires 64, 83, lever 5, in 30 raised position, wire 130, lever 17, wire 131, to green lamp G. This circuit indicates to the motorman that the train may now proceed at maximum speed indicated by the signals located on the right of way.

35 The second circuit established through lever 5, is as follows:

Retaining circuit for stick relay SR through control relay C.

40 Branching from wire 130, to wires 132, and 62, to coil PW, of relay SR, returning to battery through wire 78, and ground on car X¹. This circuit serves to keep stick relay SR, energized during all periods when 45 control relay C, is energized and serves particularly to keep stick relay SR, from opening as the stick circuit for stick relay SR is opened by a contact shoe passing over a clear ramp as heretofore described.

50 *Brief summary of operations required to place a train, or car, as X¹, in service.*

From the foregoing it may be briefly stated that, for a motorman to place a train, 55 or car as X¹, in service, it is first necessary to insert and rotate a key in device KS¹, or KS², thereby simultaneously closing a circuit permitting movement of said train, or car under its own power; opening the circuit to valve EPV, and applying brakes to train thereby checking the mechanical integrity of said valve; and lastly closing a circuit to the yellow, or caution cab signal Y, thereby indicating the automatic train 60 control apparatus on the said car has been 65

placed in service. A predetermined time after said valve has operated, and after a further manual reduction of brake pipe pressure, the motorman presses the reset button and picks up stick relay SR, which in turn restores the said valve EPV. The train thereafter moves out upon the roadway, and, as the contact shoe CS², is raised by engagement with a clear ramp, as 1^B, at proper speed, slow acting relay SAR, completes its movement, and, thereby as said shoe leaves the ramp picks up control relay C, and said control relay picks up stick relay SR, at the same time extinguishing the caution cab signal Y, and lighting the proceed cab signal G.

Description of apparatus and circuits in Fig. 2.

As circuits and apparatus on train X¹, 85 are now arranged to permit said train to travel freely subject to signals and automatic train control apparatus on the roadway and are arranged substantially as shown in Fig. 1, assume said train to be traveling in block 90 B, Fig. 2, and in the direction of arrow W, in block D.

Blocks A, B, C, D, and E, are of the well known construction constituting a track circuit having track batteries as TBA, to TBD, 95 inclusive, or their equivalent, co-operating with track relays as TRA, to TRD, inclusive or their equivalent. The rails 45, of each block are substantially insulated from each other by insulated joints 44. Arranged 100 alongside the roadway and controlled by track relays TRA, to TRD, inclusive, are signals SA, to SD, inclusive. These may be of the semaphore type as shown, or of the light signal type, both of well known construction. Said signals are arranged to indicate three positions, or indications, proceed, caution, and stop. The last indication, in my improved system permits a train to enter an occupied block at a predetermined 110 reduced speed. Said signals are operated from batteries, or their equivalent, not shown, and in a manner well known to those skilled in the art of signaling. Further said signals are arranged to control each other as 115 follows: assume a signal to indicate stop as signal SC, Fig. 2. By means of line wire 4^C, signal SB is made to indicate caution as shown. This is known as "line control" for 3 position signals. Another method known 120 as polarized control is illustrated in my application for Letters Patent Serial #113,064 filed November 4th, 1916. Track relays TRA, to TRD, inclusive are also arranged to short circuit ramps as 1^B, 2^B, 3^B, to 1^D, 2^D, 3^D, 125 inclusive to track rails 45, at such times as said track relays are de-energized by presence of a train, as X¹, or other well known cause, as for example the breaking of a rail 45. The method of short circuiting is fully de- 130

scribed in Letters Patent #1,101,511 granted to me June 23rd, 1914, and also in my application for Letters Patent Serial #113,064 as above named.

5 For the purpose of simple illustration, in the accompanying drawing it is shown as being accomplished as follows:

Portion of reduce speed circuit on roadway.

- 10 From lower track rails 45, wire 8^c, lever 9^c, wires 5^c, 6^c, and 7^c, to ramps 1^c, 2^c, and 3^c, said ramps act as the means for obtaining the indication from the right of way to trains.
- 15 As all the apparatus and operations thereof shown in Figs. 3, 4, and 5, are substantially the same as that illustrated in Fig. 2, no further description is required except as special forms and construction arises and as 20 pointed out in the progress of description of the various figures.
- As the prime object of my improved system is to obtain maximum capacity of traffic on a railway system, all blocks, as A, to D, 25 inclusive are preferably of a length equal to the service braking distance of the train, or car, as X¹, in any given block. It will be noted blocks B, C, and D, are of equal length, it being assumed that the roadway at 30 this point is level, that is, without plus, or minus grade, and further that no curve exists, and in which case the braking, or reduce speed curve will be substantially in accordance with curve Z, shown in Fig. 2.
- 35 As before described train X¹, has passed over a clear ramp, as 1^b. As said train proceeds in the direction of arrow W, and contact shoe CS², engages and passes over clear ramps as 2^b, and 3^b, no change in relation 40 of circuits takes place as the shoe leaves the ramp. However it should be noted that as a shoe, as CS², passes onto a clear ramp as 2^b, or 3^b, the direct EPV valve circuit through contact shoe is established and maintained during substantially the entire period 45 the shoe is on the ramp. Also the stick circuit for stick relay SR is opened by either lever 30, or 39, however relay SR, is prevented from opening as energy is supplied 50 through lever 5, of control relay C, which does not open. Also the slow acting relay circuit is established and said relay begins to raise its levers 1, 2, and 3, however, whether its movement is completed or not, 55 no change in relation of relays takes place.

Entrance of train X¹ into a caution block.

Assume now that train X¹, is approaching caution signal SB, at the entrance to block C, Fig. 2. It is to be noted that presence of train X² in block D, has placed signal SC, at stop therefore moving signal SB, to caution. At the point of reaching said signal SB, or slightly before, the motorman of 65 train X¹, makes a full service application of

the brakes thereby reducing the speed of train X¹, substantially in accordance with curve Z. As track relay TRC, is deenergized ramps 1^c, 2^c, and 3^c, are short circuited to rails 45. Therefore as contact shoe, as CS², 70 contacts with the first caution ramp 1^c, control relay C, is shunted out by a partial circuit on the train as follows:

Portion of reduce speed circuit on train X¹. 75

From battery SB, wires 46, 47, fuse 48, wire 63, lever 22, wires 64, 65, 124, 125, resistance 126, lever 4, wire 127, shoe CS¹, wire 128, shoe CS², thereafter passing through the portion of reduce speed circuit 80 on roadway as follows, ramp 1^c, wire 5^c, lever 9^c, wire 8^c, rails 45 to wheels and frame of train X¹, returning to battery SB, thereby completing the reduce speed circuit. As relay C, is deprived of current by the shunt circuit, above described, it opens and as lever 4 lowers it thereby opens said shunt circuit, that is the portion of reduce speed circuit on train X¹, and in this manner preventing said control relay from picking up as the 90 shoe leaves the ramp. Further, by opening said portion of reduce speed circuit on train X¹ waste of energy in resistance 126, is avoided.

Simultaneous with establishing the complete reduce speed circuit as shoe CS² contacts with ramp 1^c, the slow acting relay circuit is also established, and assuming train X¹, to be reducing speed in accordance with curve Z, the ramp is of such length that 100 slightly greater than one second will be consumed by said shoe in passing the entire length of the ramp. Therefore slow acting relay SAR, completes its movement and raises levers 1, 2, and 3. By this performance the pick-up circuit for stick relay SR, through slow acting relay SAR is established energizing said stick relay SR, thereby raising levers 7, 8, 9, and 10, said levers establishing the several circuits heretofore 110 described.

It will be noted that as relay SAR, has completed its movement, the pick-up circuit for control relay C, is established as shoe CS², leaves the ramp 1^c, however as the complete reduce speed circuit still exists by virtue of ramp 1^c, being short circuited to rail 45, said control relay C, will not be energized and levers 4, and 5, remain in lowered position. Lever 5, therefore maintains the caution cab signal Y, burning, this being the proper signal to retain throughout a caution block, as C.

As contact shoe CS², passes over ramps 2^c, and 3^c, a like cycle of operations takes place, 125 except of course that control relay C, is open and therefore stick relay SR, is opened through the stick circuit for stick relay SR, as the shoe engages said ramps. The foregoing is of course on the assumption that 130

said train X^1 , continues to reduce in speed substantially in accordance with curve Z , as shown.

Assume however, that motorman has failed 5 to observe caution signal SB , and train X^1 , proceeded into block C , at maximum speed. Under these conditions contact shoe CS^2 , would consume less than one second to pass over ramp 1^c , thereby preventing slow acting 10 relay SAR , from completing its movement and establishing the pick-up circuit for stick relay SR , through slow acting relay SAR , and, as the shoe leaves the ramp and opens the direct EPV circuit through shoe by lever 15 28, said valve EPV , operates and makes an emergency brake application throughout said train. Its speed therefore is reduced substantially in accordance with the dotted curve ZE . Said curve ZE , is assumed to be 20 the emergency braking curve for the particular braking equipment supplied on train, as X^1 . It will be noted that a maximum speed of 50 miles per hour is represented and that as the contact shoe CS^2 , leaves the 25 ramp 3^c , the speed, assuming speed reduction in accordance with curve Z , must have been reduced to 15 miles per hour or less. Train X^1 , may therefore enter occupied block D , at reduced speed, or "under control," and 30 travel up to a preceding train, in this manner permitting "closing up" of trains and facilitating traffic.

Assume that as train X^1 , entered caution block C , train X^2 were accelerating and 35 passed from block D , to block E , signal SD , would move to stop, signal SC , to caution and signal SB , to clear position. As track relay TRC picks up by train X^2 clearing block D , the short circuit between ramps 1^c , 40 2^c , 3^c , and rails 45, is removed, changing said ramps to clear ramps. As signal SC , changes from stop to caution indication the motorman is informed that he may release brakes and accelerate his train to a speed 45 which, if required, will permit a succeeding speed reduction, as curve Z , in block D .

Assuming that contact shoe CS^2 , has not left ramp 1^c , as track relay TRC , picks up, as said shoe leaves the ramp the control relay C , is energized thereby raising levers 4, and 5, extinguishing the caution cab signal Y , and lighting the proceed cab signal light G , thereby checking the performance of the 50 automatic train control apparatus on the 55 train and also giving additional information to the motorman of the change in signal indications as named.

If relay TRC had not picked up until after shoe CS^2 , had left ramp 1^c , the green, 60 or proceed cab signal G , would be established as shoe CS^2 , left ramp 2^c , and motorman would thereafter accelerate his train as before described.

It is evident therefore that ramps, as 1^c ,

2^c , and 3^c , act as releasing points if a train 65 has entered a caution block as C , and said block clears up with said train still present in the block. In this manner capacity is increased over a system where it would be necessary to continue reducing speed until 70 the end of the block is reached and as, for example, is required in the system described in Letters Patent #1,150,306 granted to P. J. Simmens under date of August 17, 1915.

Further it should be noted that if conditions on roadway should warrant longer or shorter blocks than shown due to different braking curves, as Z , it only becomes necessary to change length or spacing, or both, of ramps as 1^c , 2^c , 3^c , or others shown. 80 Further as said ramps are local to the right of way, any number of changes, or new blocks may be added without affecting the automatic train control apparatus on the train as X^1 . From the foregoing it is evident 85 that my improved system is flexible.

Further, it will be noted that ramps, as 1^a , 2^a , and 3^a , of predetermined length in combination with the automatic train control apparatus on trains, as X^1 , are the 90 means for developing the "speed reduction curves" as Z , and that said ramps also serve as the means for obtaining the indication from the right of way to said trains, in other words, said ramps accomplish two purposes.

Description of train X^1 entering unsignaled territory.

Referring to Fig. 3, which is assumed to 100 be part of the roadway illustrated in Fig. 2. As before stated this view shows the various circuits and apparatus employed in connection with certain circuits and apparatus on train X^1 , which permits said train 105 to travel from signaled territory to unsignaled territory, at the same time establishing proper cab signals on said train informing the motorman of such change. This part of my improved system of automatic 110 train control is fully described in my application for Letters Patent Serial #129,817 filed November 6th, 1916. However a brief description will be given pointing out the various circuits and apparatus in Figs. 1, 115 and 3. Referring to Fig. 3, permanent clear ramps 1^a , and 2^a , are placed on opposite sides of roadway and will be termed right and left hand ramps. Ramp 2^a , is placed a distance ahead of ramp 1^a , substantially 120 the distance between the centers of contact shoes CS^1 , and CS^2 . The leaving ends of ramps have a long gradual slope as V , $-V$, both of substantially the same length and degree of angularity.

Assume that train, as X^1 , has entered block H , with clear signals and that its contact shoes are on ramps 1^a , and 2^a , as shown.

Under these conditions the following circuit is established:

Unsignaled territory circuit.

- 5 From battery SB, on train X^1 , wires 46, 47, fuse 48, wire 63, lever 22, wires 64, 65, 66, 67, 68, 69, 133, lever 42, wire 134, lever 33, wire 135, lever 10, wires 136, 137, to coil of unsignaled territory relay UT, returning to battery SB, through wire 138, and ground. As relay UT, is energized it raises levers 15, 16, and 17. Lever 15 establishes the following partial circuit:

15 *Stick circuit for unsignaled territory relay UT.*

- From battery SB, wires 46, 47, fuse 48, wire 63, lever 22, wires 64, 65, 66, 67, 87, 88, 93, 112, 113, resistance 114, to lever 27. 20 As shoes CS^1 , and CS^2 lower on inclined portions V—V, of ramps 1^H, and 2^H, levers 27, and 36, close simultaneously and complete circuit as follows, from lever 27, wire 115, lever 36, wires 116, 139, lever 15, wires 25 140, 137, to coil of relay UT, returning to battery through wire 138, and ground. Contact levers 27, and 36, are arranged to make contact before levers 33, or 42, opens as shoe lowers on said inclines. They are 30 known as "make before break" contacts.

As lever 17, of relay UT, raises it opens the circuit to the green, or proceed cab signal G. However lever 16, in raising establishes a circuit to the white light W, and 35 valve EPV, as follows:

Unsignaled territory cab signal circuit.

- From battery SB, wires 46, 47, fuse 48, wire 63, lever 22, wires 64, 65, 124, 141, 40 142, 143, lever 16, wire 144, 167, white light W, returning to battery through ground. This circuit serves to continually inform the motorman, or operator of train, as X^1 , of the fact that his train is traveling in territory not equipped with signals, and that, 45 therefore he must control his train accordingly.

To valve EPV, via wires 168, 108, 81, and 53.

- 50 As a train, as X^1 , again enters signaled territory traveling in the normal direction of traffic, as pointed out by arrow W, the stick circuit for unsignaled territory relay UT, is opened by lever 27, or 36 as the first 55 ramp is engaged whether right, or left hand. Also the green, or proceed, or the yellow, or caution light is illuminated dependent upon whether a clear, or caution ramp is first encountered. A marker, or 60 signal, as NS, is placed at the entrance to unsignaled territory, J, as shown, thereby forming a permanent indication at that point.

The various relays, batteries and ramps

shown in blocks F, and G, are similar to 65 those employed in Fig. 2, and their function therefore will be well understood.

Description of train X^1 approaching absolute stop territory.

70

Referring to Fig. 4, which also is assumed to be part of the roadway as shown in Figs. 2, and 3. As before stated this view illustrates certain circuits and apparatus employed in connection with certain 75 circuits and apparatus as shown in Fig. 1, for compelling a train as X^1 , to come to an "absolute stop" when approaching a point of extreme hazard, such as a railway crossing shown in block N. Blocks K, and L, are 80 equipped with usual relays, batteries, signals, ramps, and other apparatus described in connection with Fig. 2, and their function therefore will be well understood. In block M, two additional ramps 10^M, and 11^M, have been added. It is to be noted that ramp 10^M, is longer and further, is placed in advance of ramp 11^M. The distance DM, between their leaving ends is slightly less than the distance between the centers of 90 contact shoes CS^1 , and SC^2 . This staggered leaving end prevents setting up the unsignaled territory circuit falsely if a train is proceeding under clear signals, and further, if required, establishes the "against 95 traffic" circuit, as will be more fully herein-after described.

As a train, as X^1 , approaches in the direction of arrow W, and assuming that speed is reduced substantially in accordance with 100 curve Z, of Fig. 4. Owing to the double stop indication shown by signal SM, motorman will stop his train before reaching, or just opposite said signal. It is assumed for purposes of illustration and description that if train, as X^1 , stops opposite the signal SM, its contact shoe CS^2 , will be on the first half of ramp 3^M. Under these conditions no change in relation of circuits and apparatus established by a caution block 105 takes place, and as signal SM, is cleared to show two clear indications, or two caution indications ramps 3^M, 10^M, and 11^M, become 110 clear ramps, and as train proceeds and shoe CS^2 , leaves ramp 3^M, the proceed cab signal circuit is established in a manner heretofore described. It should be stated that signal SM, and line relay LRM, are controlled from the interlocking tower I. T. shown as a rectangle in block N. This form of control is well known to those skilled in the signaling art. It may be manual, or semi-automatic, dependent upon the type of interlocking apparatus installed in and about the tower I. T.

Assume however that after having reduced speed in accordance with curve Z, the motorman violates the "absolute stop" sig-

120

125

nal SM, and proceeds until contact shoe CS², engages ramp 10^M, and shoe CS¹, ramp 11^M and both shoes are raised thereby. It will be remembered that by virtue of passing 5 over caution ramp 3^M, that the control relay C, is deenergized.

As the shoe CS², engages the ramp 10^M, the slow acting relay circuit is established and said relay begins its movement, however 10 as shoe CS¹, is raised by engagement with ramp 11^M, the circuit to said relay is opened by virtue of both levers 41, and 32, cutting battery off of the said circuit. Further it will be noted that while the direct EPV circuit 15 through contact shoe is established by lever 28, said circuit is thereafter opened by lever 38, as shoe CS¹, raises on ramp 11^M. Valve EPV is now deprived of current from battery SB, and operates to apply the emergency application of brakes, thereby positively stopping the train.

As passing an absolute stop signal is a gross violation of orders it must be dealt with severely.

25 Pressing of reset button is of no avail as stick relay SR, will not stick up through lever 3, as the slow acting relay is deenergized. It is necessary therefore for the motorman to leave his cab, proceed to a compartment containing the valve EPV, break a seal and operate a valve, not shown, said valve closing the communication between the brake pipe and valve EPV. Thereafter brakes can be released and train may 30 proceed off the absolute stop ramps 10^M, and 11^M. It is assumed that unless breaking of said seal can be accounted for by defective apparatus on said train that it is an indication of immediate dismissal of motorman 35 committing such act.

Description of operation of train X¹ in connection with Fig. 5.

Referring to Fig. 5, which is also assumed 45 to be part of roadway as shown in Figs. 2, 3, and 4. As before stated Fig. 5, is a diagrammatic illustration of circuits and apparatus along the roadway employed in connection with certain circuits and apparatus 50 on train, as X¹, to compel said train to operate under a predetermined reduced speed over portions of roadway where it would be hazardous to travel in excess of such reduced speed, as for example, down a 55 steep grade, or around a sharp curve.

The various track relays, batteries, signals, and ramps with accompanying accessories are similar of construction and function to 60 those of Fig. 2, except as will be specially described as the description progresses. It will be noted that ramps 1^Q, and 1^R, are permanently grounded to rails 45, by wires 14^Q, and 14^R. Signals SP, SQ, and S8, are 65 equipped with an additional lower indication, which for the particular purposes here-

in described are permanently caution. Said signals are also equipped with markers as 25, within a circle, indicating the maximum speed at which a train may proceed through said reduced speed territory.

Assume train, as X¹, to be traveling in block P, and approaching signal SP. By means of the lower permanent caution indication and marker 25, motorman is advised that he must, on or before reaching signal SP, make a full service application of the brakes and reduce train speed to not in excess of 25 miles per hour, and further continue at such speed until the next single indication clear signal is reached, as S8, assuming, of course that no preceding train, as X², is present.

As ramps 1^Q, and 1^R, are permanent caution ramps, the train must by virtue of conditions as heretofore described consume one 85 second or more in passing over such ramps. Train must therefore reduce speed substantially in accordance with curve Z, to prevent the emergency application as the contact shoe leaves ramp 1^Q. Further assuming blocks 90 R, and S, to be normal it must continue at such reduced speed to prevent said emergency application when leaving ramp 1^R.

As signal S8, is sighted motorman is informed that maximum speed can again be 95 resumed. For purpose of illustration it is assumed to be sighted as train X¹, leaves ramp 1^R. Motorman thereafter accelerates his train in accordance with curve ZB.

If a train as X², had been present in block 100 S, a following train, as X¹, would find signal SQ, with a double caution indication, as shown. Further as ramps 2^R, and 3^R, are also caution ramps, said train X¹, would be required to reduce speed substantially in accordance with dotted curve ZA as shown.

It is to be noted that, if required, permanent caution ramps, as 1^Q, and 1^R, may be placed intermediate ramps 2^Q, and 3^Q, or 2^R, and 3^R, and likewise between 3^Q and 1^R, in 110 this manner enforcing more close running to the horizontal line connecting curves Z, and ZB, and which represents in this instance 25 miles per hour.

Description of against traffic movement. 115

Assume now that because of one of several reasons well known to railway operators, as for example, repair of the roadway, it becomes necessary to operate trains in a direction opposite to arrow W, as shown, and which is known as "against traffic" movement, and as is fully described in my application for Letters Patent Serial #128,817 filed November 1st, 1916. However a brief description will be given pointing the various circuits and apparatus shown in the accompanying drawings.

Before beginning such against traffic movement the motorman rotates and removes the 130

key 6, from device KS^1 thereby cutting car out of service and supplying energy to the EPV valve through the out of service EPV circuit heretofore described. He also places 5 master controller MC^1 , in neutral position, and goes to the opposite end of train. Assume for purposes of illustration that car X^1 , is a single car train as before described.

The motorman inserts and rotates key 6, 10 in device KS^2 , thereby raising levers 24, 25, and 26, and at the same time placing master controller MC^2 , in the forward position, F. Under these conditions the various functioning of devices takes place, and as described 15 under placing car X^1 in service, leaving the caution cab signal illuminated.

It will be noted that normal operating ramps, as 2^B , and 3^B , are now on the left hand side of motorman and therefore will 20 be termed left hand ramps.

Assume that train X^1 , in its against traffic movement is about to pass from block D, to block C, Fig. 2. It will be noted that due to the presence of train in block D, ramps 1^C , 25 2^C , and 3^C , are all caution ramps. As shoe CS^2 , engages and raises upon ramp 3^C , the following circuit is established:

Against traffic pick-up circuit.

30 From battery SB, wires 46, 47, fuse 48, wires 49, 156, lever 26, wires 157, 66, 67, 68, 69, 103, lever 41, wires, 104, 105, 111, 145, lever 24, wire 146, lever 34, in raised position, wires 147, 148, to coil of against traffic 35 relay AT, returning to battery through wire 149, and ground. If said train were likewise proceeding against traffic but operated from master controller MC^1 , and in which case shoe CS^1 would be the left hand shoe. 40 and contacting with normal traffic ramps, the circuit would have been completed as follows: from battery SB, wires 46, 47, fuse 48, wire 63, lever 22, wires 64, 65, 66, 67, 87, 109, lever 32, wires 110, 111, 105, 151, lever 45 20, wire 152, lever 43, wires 153, 148, 149, to said relay AT.

It will be noted that as shoe CS^2 , engages left hand caution ramps as 3^C , the control relay C, and stick relay SR, open in a manner heretofore described. Further as the against traffic relay AT, picks up it opens the pick-up circuit for stick relay SR through slow acting relay SAR through lever 165, and therefore said stick relay can 50 not pick up even though the slow acting relay SAR, completes its movement as shoe CS^2 , passes over the several ramps on the roadway.

As lever 9, of stick relay SR, lowers, and 60 by virtue of against traffic relay being energized through its pick-up circuit, the following circuit is established:

Against traffic relay stick up circuit.

65 From battery SB, wires 46, 47, fuse 48,

wires 49, 156, lever 26, wires 157, 66, 67, 68, 154, lever 9, wire 122, lever 11, wire 149, to coil of relay AT, returning to battery through wire 150, and ground. If master controller MC^1 , and device KS^1 , had been 70 in service with train likewise traveling against traffic, the circuit would have been completed as follows: from battery SB, wires 46, 47, fuse 48, wire 63, lever 22, wires 64, 65, 66, 67, 68, 154, lever 9, wire 122, 75 lever 11, wire 149, to coil of relay AT, returning to battery through wire 150, and ground. This circuit serves to keep relay AT, energized until such times as said against traffic movement ceases, at which 80 time energy is cut off the system by lever 26, or in the case of resetting by lever 9.

It is to be noted that as said relay AT, is energized and raises levers 11, 12, 13, 14, and 165, that lever 12, supplies energy to 85 valve EPV, as follows:

EPV Circuit through against traffic relay AT.

From battery SB, wires 46, 47, fuse 48, 90 wires 49, 156, lever 26, wires 157, 124, 141, 142, 158, lever 12, wires 159, 108, 81, 53, to valve EPV, returning to battery through wire 82, and ground. Therefore said valve is maintained inoperative as long as relay 95 AT, is energized and train may move freely in the direction "against traffic."

Lever 13, closes a circuit to red lamp R, as follows:

Against traffic cab signal circuit.

100 From battery SB, through circuit just previously traced to wire 141, thence to wire 160, lever 13, wire 161, red lamp R, returning to battery SB, through ground. The 105 object of this circuit is to continuously warn motorman that train, as X^1 , is proceeding under conditions abnormal, and with some considerable hazard, as other trains preceding may be moving slowly, 110 or maintainers on the right of way may not know of such against traffic movement. In addition to the red lamp it is even desirable to have an audible signal which continually sounds while said relay AT, is energized. 115 This however is not shown.

Lever 14, opens the circuit to the yellow lamp Y, as the red lamp R, is illuminated and which is obviously correct.

Device 163, is preferably an incandescent 120 lamp which lights each time either shoe CS^1 , or CS^2 , is raised in passing over a ramp. Its circuit is designated as:

Shoe checking circuit.

125 From battery SB, through the same circuit as described for the slow acting relay circuit branching from wire 90, or 102, to wire 164, to device 163, returning to battery SB, through ground. The object of this 130

circuit is to indicate the proper functioning of either shoe CS¹, or CS², in passing over a ramp, as 2^h.

It may be stated that the art teaches fully how, if so desired, indications may be given from the right of way to the traveling train, or vehicle.

Further, how to employ alternating, as well as direct currents if the former is preferred.

Finally it is known that the operator of a vehicle or train, if so desired, may be compelled to manually operate signal apparatus on the train in co-operation with the apparatus on the right of way, at such times as he is entering a zone of hazard.

It will also be noted that the stick circuit for control relay C, is carried through the contacting portions of shoe CS¹, and CS². Therefore should said shoes be torn off by an obstruction on the roadway, said circuit will open thereby opening relays C and SR, and applying brakes to the train, as X¹.

These and other operations or means are applicable to my system and are referred to to show its extreme flexibility and value generally as a means of automatically controlling the speed of trains. The invention as I have indicated, does not depend upon the use of any specific form of apparatus for accomplishing the functions and purposes hereinbefore set forth.

What I claim is,

1. In a system of automatic train control, a roadway, a vehicle adapted to travel thereon, said roadway comprising automatically controlled zones adapted to compel the operator of said vehicle to reduce its speed in accordance with predetermined speed reduction curves when approaching a zone of hazard, automatically controlled zones adapted to compel said operator to absolutely stop said vehicle when approaching a zone of extreme hazard, and non-automatically controlled zones adapted to compel said operator to cause said vehicle to travel at substantially continuous predetermined reduced speed substantially as described.

2. In a system of automatic train control, a roadway, a vehicle adapted to travel thereon, automatic stop devices carried thereby, said roadway comprising automatically controlled zones adapted to control said automatic stop devices whereby, to prevent their operation, the operator of said vehicle is compelled to reduce its speed in accordance with predetermined speed reduction curves when approaching a zone of hazard traveling in the normal direction of traffic, automatically controlled zones adapted to control said automatic stop devices whereby, to prevent their operation, the operator in addition to reducing the speed of said vehicle in accordance with predetermined speed reduction curves, is compelled to absolutely

stop said vehicle when approaching a zone of extreme hazard, and means to annul said automatic stop devices when said vehicle travels in a direction against the normal direction of traffic irrespective of which end 70 of the vehicle is foremost, substantially as described.

3. In a system of automatic train control, a vehicle, automatic stop devices carried thereby, automatically controlled means for preventing the operation of said stop devices dependent for operation upon the reduction of speed of said vehicle in accordance with a predetermined speed reduction curve when traveling in a normal direction 80 of traffic and means for annulling the operation of said stop devices and said controlling means when said vehicle travels in a direction against the normal direction of traffic irrespective of which end 85 of the vehicle is foremost.

4. In a system of the kind described, a vehicle, a roadway therefor, a normally energized electro-pneumatic valve for automatically stopping said vehicle, a relay controlling said valve, a manually operated circuit controlling device, a circuit for energizing said relay dependent for closure on the de-energization of said valve and manual operation of said circuit controlling device. 90

5. In a system of automatic train control, a vehicle, a roadway therefor, normally energized means for automatically stopping said vehicle, means controlling said stopping means, a circuit closer, means for energizing 100 said controlling means dependent for operation on the de-energization of said automatic stopping means and operation of said circuit closer.

6. In a system of automatic train control, a vehicle, a roadway therefor, normally energized means for automatically stopping said vehicle, means controlling said stopping means, a normally open circuit closer, means for energizing said controlling means dependent for operation on the de-energization 110 of said automatic stopping means and closing of said circuit closer, substantially as described.

7. In a system of automatic train control, a vehicle, a roadway therefor, normally energized means for automatically stopping said vehicle, means controlling said stopping means, automatic means controlling said controlling means, means for energizing 120 said controlling means, a normally open circuit closer, said energizing means being dependent for operation on the de-energization of said automatic stopping means and the closing of said circuit closer, substantially as described.

8. In a system of automatic train control, a self-propelled vehicle, a roadway therefor, normally energized means for automatically stopping said vehicle, automatic controlling 130

- means on said roadway adapted to control said stopping means, means for operating said vehicle, and means for simultaneously rendering inoperative said operating means 5 and the control of said automatic stopping means by said controlling means, substantially as described.
9. In a system of automatic train control, a self-propelled vehicle, a roadway therefor, means for automatically stopping said vehicle, automatically controlled zones on said roadway controlling said automatic stopping means whereby, to prevent their operation the operator of said vehicle is compelled 10 to reduce its speed in accordance with predetermined speed reduction curves, means for controlling the propulsion of said vehicle, and means for simultaneously rendering inoperative said means controlling the propulsion of said vehicle and annuling the effect of said controlling zones to control said stopping means, substantially as described.
10. In a system of automatic train control, a self-propelled vehicle, a roadway therefor, means for automatically stopping said vehicle, automatically controlled zones on said roadway normally controlling said automatic stopping means whereby to prevent 15 their operation said vehicle is compelled to reduce its speed in accordance with predetermined speed reduction curves, means for controlling the propulsion of said vehicle, and means for simultaneously rendering inoperative said propulsion control means and annuling the effect of said controlling zones to control said stopping means substantially as described.
11. In a system of the kind described, comprising a self-propelled vehicle, a roadway for said vehicle, automatically controlled means on said vehicle, in combination with automatic controlling means on said roadway for enforcing the reduction of the speed of said vehicle substantially in accordance 20 with predetermined speed curves, means for operating said vehicle, means for applying brakes to said vehicle, and means for simultaneously rendering said automatically controlled means, responsive to said controlling means, and operating said means for applying brakes to said vehicle, substantially as described.
12. In a system of automatic train control, a self-propelled vehicle, a roadway therefor, means for automatically stopping said vehicle, automatically controlled zones on said roadway normally adapted to control said automatic stopping means, whereby to prevent their operation said vehicle is compelled 25 to reduce its speed in accordance with predetermined speed reduction curves, means for controlling the propulsion of said vehicle, and manually operated means for simultaneously rendering inoperative said
- propulsion control means and annuling the effect of said controlling zones to control said stopping means, substantially as described.
13. In a system of automatic train control, a self-propelled vehicle, a roadway therefor, means for automatically applying brakes to said vehicle, automatically controlled zones on said roadway adapted to control said brake applying means whereby, to prevent their operation the operator of said vehicle is compelled to reduce its speed in accordance with predetermined speed reduction curves, means controlling the propulsion of said vehicle, and means 30 controlling said propulsion control means and said brake applying means whereby, to render said propulsion control means operative said brake applying means is actuated to apply the brakes to said vehicle, substantially as described.
14. In a system of automatic train control, a self-propelled vehicle, a roadway therefor, means for automatically applying the brakes to said vehicle, automatically controlled zones on said roadway adapted to control said brake applying means whereby, to prevent their operation the operator of said vehicle is compelled to reduce its speed in accordance with predetermined speed reduction curves, means controlling the propulsion of said vehicle, and manually operated means controlling said propulsion control means and said brake applying means whereby, to render said propulsion control 35 means operative, said brake applying means is actuated to apply the brakes to said vehicle, substantially as described.
15. In a system of automatic train control, a vehicle, a roadway therefor, means for automatically stopping said vehicle, automatically controlled zones on said roadway adapted to control said automatic stop means whereby, to prevent their operation the operator of said vehicle is compelled to reduce its speed in accordance with predetermined speed reduction curves when approaching a zone of hazard, and automatically controlled zones on said roadway adapted to control said automatic stop means whereby to prevent their operation the operator of said vehicle, in addition to reducing its speed in accordance with said speed reduction curves, is compelled to absolutely stop said vehicle when approaching a zone of extreme hazard, substantially as described.
16. In a system of automatic train control, a vehicle, a roadway therefor, comprising signaled and unsignaled territory, means for automatically stopping said vehicle, automatically controlled zones on said roadway adapted to control said automatic stop means whereby, to prevent their operation the operator of said vehicle is compelled

- to reduce its speed in accordance with pre-determined speed reduction curves when approaching a zone of hazard, automatically controlled zones on said roadway adapted 5 to control said automatic stop means whereby, to prevent their operation the operator of said vehicle, in addition to reducing its speed in accordance with said speed reduction curves, is compelled to absolutely stop said 10 vehicle when approaching a zone of extreme hazard on said roadway, and means annulling the control of said automatic stop means by said automatically controlled zones as said vehicle passes from said signaled to 15 said un-signaled territory, substantially as described.
17. In a system of automatic train control, a vehicle, a roadway therefor, means for automatically stopping said vehicle, automatically controlled zones on said roadway adapted to control said automatic stop means whereby, to prevent their operation the operator of said vehicle is compelled to reduce its speed in accordance with pre-determined speed reduction curves when approaching a zone of hazard traveling in the 20 normal direction of traffic, automatically controlled zones on said roadway adapted to control said automatic stop means whereby, to prevent their operation the operator of said vehicle, in addition to reducing its speed in accordance with pre-determined speed reduction curves when approaching a zone of hazard traveling in the normal direction of traffic, automatically controlled zones on said roadway adapted to control said automatic stop means whereby, to prevent their operation the operator of said vehicle, in addition to reducing its speed in accordance with pre-determined speed reduction curves, is compelled to absolutely stop said vehicle when approaching a zone of extreme hazard traveling in the normal direction of traffic, controlling zones 25 on said roadway adapted to annul the control of said automatic stop means by said controlling zones as said vehicle passes from signaled to un-signaled territory and means carried by said vehicle for annuling the control of said automatic stop means by said controlling zones whereby said vehicle may travel without automatic control in a direction opposite to the normal direction of traffic, substantially as described.
18. In a system of automatic train control, a vehicle, a roadway therefor, means for automatically stopping said vehicle, automatically controlled zones on said roadway adapted to normally control said automatic stop means whereby, to prevent their operation the operator of said vehicle is compelled to reduce its speed in accordance with pre-determined speed reduction curves when approaching a zone of hazard traveling in the normal direction of traffic, automatically controlled zones on said roadway adapted to control said automatic stop means whereby, to prevent their operation the operator of said vehicle in addition to reducing its speed in accordance with said speed reduction curves, is compelled to absolutely stop said vehicle when approaching a zone of extreme hazard traveling in the normal direction of traffic, means for annulling the control of said automatic stop means by said controlling zones whereby said vehicle may travel 30
- without automatic train control in a direction against the normal direction of traffic, and non-automatically controlled zones adapted to control said automatic stop means whereby, to prevent their operation the operator of said vehicle is compelled to cause said vehicle to travel at substantially continuous predetermined reduced speed, substantially as described.
19. In a system of automatic train control, a vehicle, a roadway therefor comprising signaled and un-signaled territory, means for automatically stopping said vehicle, automatically controlled zones on said roadway adapted to normally control said automatic stop means whereby, to prevent their operation the operator of said vehicle is compelled to reduce its speed in accordance with pre-determined speed reduction curves when approaching a zone of hazard traveling in the normal direction of traffic, automatically controlled zones on said roadway adapted to control said automatic stop means whereby, to prevent their operation the operator of said vehicle, in addition to reducing its speed in accordance with pre-determined speed reduction curves, is compelled to absolutely stop said vehicle when approaching a zone of extreme hazard traveling in the normal direction of traffic, controlling zones on said roadway adapted to annul the control of said automatic stop means by said controlling zones as said vehicle passes from signaled to un-signaled territory and means carried by said vehicle for annuling the control of said automatic stop means by said controlling zones whereby said vehicle may travel without automatic control in a direction opposite to the normal direction of traffic, substantially as described.
20. In a system of automatic train control, a vehicle, a roadway therefor comprising signaled and un-signaled territory, means for automatically stopping said vehicle, automatically controlled zones in said signaled territory adapted to normally control said automatic stop means whereby, to prevent their operation the operator of said vehicle is compelled to reduce its speed in accordance with pre-determined speed reduction curves when approaching a zone of hazard traveling in the normal direction of traffic, automatically controlled zones in said signaled territory adapted to control said automatic stop means whereby, to prevent their operation the operator of said vehicle, in addition to reducing its speed in accordance with pre-determined speed reduction curves when approaching a zone of hazard traveling in the normal direction of traffic, controlling zones on said roadway adapted to annul the control of said automatic stop means by said controlling zones as said vehicle passes from signaled to un-signaled territory and means carried by said vehicle for annuling the control of said automatic stop means by said controlling zones whereby said vehicle may travel without automatic control in a direction opposite to the normal direction of traffic, substantially as described.

- signaled territory, and means carried by said vehicle for annulling the control of said automatic stop means by said controlling zones whereby said vehicle may travel without automatic control in a direction opposite to the normal direction of traffic, substantially as described.
21. In a system of automatic train control, a vehicle, a roadway therefor comprising signaled and unsignaled territory, means carried by said vehicle for automatically stopping the same, automatically controlled zones in said signaled territory adapted to normally control said automatic means whereby, to prevent their operation the operator of said vehicle is compelled to reduce its speed in accordance with predetermined speed reduction curves when approaching a zone of hazard traveling in the normal direction of traffic, automatically controlled zones in said signaled territory adapted to control said automatic stop means whereby, to prevent their operation the operator of said vehicle in addition to reducing its speed in accordance with said speed reduction curves is compelled to absolutely stop said vehicle when approaching a zone of extreme hazard traveling in the normal direction of traffic, controlling zones in said signaled territory adapted to control said automatic stop means whereby, to prevent their operation the operator of said vehicle is compelled to cause said vehicle to travel at substantially continuous predetermined reduced speed, and controlling zones at the juncture of said signaled and said unsignaled territory adapted to annul the control of said automatic stop means by the aforesaid controlling zones as said vehicle passes from signaled to unsignaled territory, and means carried by said vehicle for annulling the control of said automatic stop means by said controlling zones whereby said vehicle may travel without automatic control in a direction opposite to the normal direction of traffic, substantially as described.
22. In a system of automatic train control, a vehicle, a roadway therefor comprising signaled and unsignaled territory, means carried by said vehicle for automatically stopping the same, automatically controlled zones in said signaled territory adapted to normally control said automatic stop means whereby, to prevent their operation the operator of said vehicle is compelled to reduce its speed in accordance with predetermined speed reduction curves when approaching a zone of hazard traveling in the normal direction of traffic, automatically controlled zones in said signaled territory adapted to control said automatic stop means whereby, to prevent their operation the operator of said vehicle in addition to reducing its speed in accordance with said speed reduction curves is compelled to absolutely stop said vehicle when approaching a zone of extreme hazard traveling in the normal direction of traffic, means for controlling the propulsion of said vehicle, means for annulling the control of said automatic stop means by said controlling zones, and manually operated means for simultaneously operating the said propulsion control means and the annulling means, substantially as described.
23. In a system of automatic train control, a vehicle, a roadway therefor comprising signaled and unsignaled territory, means carried by said vehicle for automatically stopping the same, automatically controlled zones in said signaled territory adapted to normally control said automatic stop means whereby, to prevent their operation the operator of said vehicle is compelled to reduce its speed in accordance with predetermined speed reduction curves when approaching a zone of hazard traveling in the normal direction of traffic, automatically controlled zones in said signaled territory adapted to control said automatic stop means whereby, to prevent their operation the operator of said vehicle in addition to reducing its speed in accordance with said speed reduction curves is compelled to absolutely stop said vehicle when approaching a zone of extreme hazard traveling in the normal direction of traffic, means for controlling the propulsion of said vehicle, means for annulling the control of said automatic stop means by said controlling zones, and manually operated means for simultaneously operating the said propulsion control means and the annulling means, substantially as described.
24. In a system of automatic train control, a vehicle, a roadway therefor comprising signaled and unsignaled territory, means carried by said vehicle for automatically stopping the same, automatically controlled zones in said signaled territory adapted to normally control said automatic stop means whereby, to prevent their operation the operator of said vehicle is compelled to reduce its speed in accordance with predetermined speed reduction curves when approaching a zone of hazard, automatically controlled zones in said signaled territory adapted to control said automatic stop means whereby, to prevent their operation the operator of said vehicle in addition to reducing its speed in accordance with said speed reduction curves is compelled to absolutely stop said vehicle when approaching a zone of extreme hazard, controlling zones on said roadway adapted to automatically annul the control of said automatic stop means by said auto-

- matically controlled zones as said vehicle passes from signaled to unsignaled territory, means for controlling the propulsion of said vehicle, means carried by said vehicle for 5 annulling the control of said automatic stop means by said controlling zones, and means for simultaneously actuating said propulsion controlling means and said annulling means, substantially as described.
- 10 25. In a system of automatic train control, a vehicle, a roadway therefor, normally energized means for automatically stopping said vehicle, controlling means therefor, automatically controlled zones on said roadway 15 adapted to normally control said controlling means whereby, to prevent their operation the operator of said vehicle is compelled to reduce its speed in accordance with predetermined speed reduction curves when approaching a zone of hazard, a normally open 20 circuit closer, means for energizing said controlling means dependent for operation on the deenergization of said automatic stop means and closing of said circuit closer, substantially as described.
- 25 26. In a system of automatic train control, a vehicle, a roadway therefor, normally energized means for automatically stopping said vehicle, controlling means therefor, automatically controlled zones on said roadway 30 adapted to normally control said controlling means whereby, to prevent their operation the operator of said vehicle is compelled to reduce its speed in accordance with predetermined speed reduction curves when approaching a zone of hazard, a manually operated 35 circuit closer adapted to be normally open, and means for energizing said controlling means dependent for operation on the deenergization of said automatic stop means and closing of said circuit closer, substantially as described.
- 40 27. In a system of train control, a vehicle, a roadway therefor, normally energized 45 means for automatically stopping said vehicle, controlling means therefor, automatically controlled zones on said roadway adapted to normally control said controlling means whereby, to prevent their operation the operator of said vehicle is compelled to 50 reduce its speed in accordance with predetermined speed reduction curves when approaching a zone of hazard, a normally open circuit closer, means for energizing said controlling means dependent for operation on the deenergization of said automatic stop means and closing of said circuit closer, substantially as described.
- 55 28. In a system of automatic train control, a vehicle, a roadway therefor, normally energized 60 means for automatically stopping said vehicle, controlling means carried by said vehicle, controlling means adapted to normally control said automatic stop devices, automatically controlled zones on said roadway adapted to normally control said controlling means whereby, to prevent their operation the operator of said vehicle is compelled to reduce its speed in accordance with predetermined speed reduction curves when approaching a zone of hazard, a normally open circuit closer, means for energizing said controlling means dependent for operation on the deenergization of said automatic stop devices and closing of said circuit closer, means for 65 annulling the control of said controlling zones, means for controlling the propulsion of said vehicle, and means for simultaneously actuating said annulling means and said propulsion controlling means, substantially as described. 70
- 75 29. The method of placing a train equipped with automatic speed control devices in service which consists in manually freeing the master controller of the train and by the same operation causing the opening of the automatically controlled valve for stopping the train and conditioning by the same operation the automatic control devices so that they may function as intended. 80
- 85 30. The method of placing a train equipped with automatic speed control devices in service which consists in manually freeing the master controller of the train and by the same operation causing the opening of the automatically controlled valve for stopping the train and conditioning by the same operation the automatic control devices so that they may function as intended and thereafter manually closing the automatically controlled valve. 90
- 95 31. In an automatic train control device, in combination: a trackway; a train; a master controller for said train; means for locking said master controller in "off" condition; a manually operated means for unlocking said controller; a brake controlling valve and means for opening said valve by the operation of said manually operated means. 100
- 105 32. In an automatic train control device, in combination: a trackway; a train; a master controller for said train; means for locking said master controller in "off" condition; a manually operated means for unlocking said controller; a brake controlling valve and a circuit for said valve opened by the manually operated means when operated. 110
- 115 In testimony whereof, OSCAR A. ROSS has signed his name to this specification, this 8th day of January 1917.
- 120 OSCAR A. ROSS.
